J. RANDALL

TUBE SQUEEZER

Filed Nov. 10, 1924

Invention
Josephine Randall
By: John O'Brien
Atty.

UNITED STATES PATENT OFFICE.

JOSEPHINE RANDALL, OF TUCKAHOE, NEW YORK.

TUBE SQUEEZER.

Application filed November 10, 1924. Serial No. 748,840.

To all whom it may concern:

Be it known that I, JOSEPHINE RANDALL, a citizen of the United States, residing at Tuckahoe, in the county of Westchester and State of New York, have invented certain new and useful Improvements in Tube Squeezers, of which the following is a specification.

The object of this invention is to provide a simple and convenient means for squeezing collapsible tubes to discharge the contents thereof in such quantity as may be required for the intended use. Collapsible tubes are commonly used as containers for tooth paste, shaving creams, ointments, salves, paints, etc., and the contents are ordinarily discharged by squeezing the tube by hand. While the pressure should be initially applied at the closed end of the tube opposite the discharge end and then gradually advanced as the contents are discharged, this method is not ordinarily followed, and it may be said to be the common practice to squeeze the tube anywhere between its ends. Sometimes this results in breaking the joint at the closed end of the tube; sometimes it produces a crack or break in the tube, and often times it results in a loss of much of the contents of the tube which remains therein after the distorted appearance of the tube indicates to the user that it has been emptied.

It is the object of my invention to provide means whereby pressure may be applied first at the closed end of the tube and then advanced as the contents of the tube are discharged, all the time pressing the contents of the tube forward from the closed end so that finally the tube is completely emptied.

A further object of the invention is to provide means for squeezing a collapsible tube so that the danger of cracking or breaking a tube will be eliminated and the entire contents of the tube discharged through the discharge end, as required.

And a further object of the invention is to provide a bracket for suspending a tube therein until emptied and in a convenient position to discharge the contents of the tube and having means for squeezing the tube to effect the discharge of all the contents.

A further object of the invention is to provide a bracket as aforesaid having a

convenient means provided for supporting such articles as artist's brushes, palette knives, tooth brushes or such other articles as may be used in connection with the contents of the tube in the tube squeezer. 60

A further object of the invention is to provide such a bracket having a convenient means provided for receiving the cap of the tube in the tube squeezer, when the tube is being squeezed and the contents 65 forced therefrom, and having means to catch any of the contents of the tube which may escape therefrom.

In the accompanying drawings I have illustrated a selected embodiment of the 70 invention, and referring thereto

Fig. 1 is a perspective view showing a tube suspended in a bracket and embodying the invention.

Fig. 2 is a transverse sectional view of the 75 invention as shown in Fig. 1.

Fig. 3 is a horizontal sectional view through the squeezing key of Fig. 1.

Fig. 4 shows in perspective a portion of 80 a tube and a squeezing key in relation for engagement therewith.

Fig. 5 is a plan view of a key blank, and

Fig. 6 is a perspective view of the key made from the blank of Fig. 5.

Referring to the drawings, the bracket 85 comprises a back support plate 7, pressed out at 7' to give rigidity thereto, adapted to be affixed to a wall, for example, and which is provided with two side plates 8, in which the squeezing key 9, is rotatably 90 mounted. The preferred form of key for use with the bracket has a head 10, a grooved shank 11, and a threaded end 12, to receive the securing nut 13. An inclined top plate 14, preferably made integral with 95 the side plates 8, is provided with a plurality of holes 15, and a curved lip 16, in which a plurality of slots 17 are provided.

The holes 15 form convenient means for holding the cap 18 of a tube 19 supported 100 in the bracket, when the tube is being squeezed to discharge some of the contents, holes of various sizes being provided to accommodate various sizes of caps.

The curved lip 16 forms a convenient 105 means for holding a tooth brush, palette knife or other article used in connection with the contents of the tube, the slots in the lip being provided as holders for tooth brushes or the like. The top plate 14 and 110

side plates 8 are secured to the back support plate 7, in any suitable manner.

At the lower end of the back support plate 7, I find it desirable to provide a drip cup 20 which may conveniently be formed as an integral part of the back plate.

In practice, the closed end 21 of the tube 19 is engaged with the slot in the shank of the key 9 while the latter is mounted in the 10 bracket and then the head 10 is turned to wind the tube upon the key. As it is wound upon the key the contents of the tube are forced towards the discharge end of the tube, which is ordinarily closed by a cap 18.

15 As the tube is wound up on the key it becomes more and more flattened out, so that substantially the entire tube can be wound upon the key in a device having substantially the proportions illustrated in the 20 drawings. When the tube has been emptied of its contents, the nut 13 is removed and the key is pulled outward from engagement with the tube and the bracket, whereupon the tube will drop out of the bracket; and then 25 the key can be replaced to receive another tube. I have found in practice that with this invention the tube is completely emptied of its contents without damage to the tube, although it will be distorted and flattened in 30 a manner readily understood.

The back support plate provides protection for the wall from the contents of the tube and the drip cup 20 provides protection to the floor or whatever is below the 35 tube by catching any of the contents which may drop or ooze therefrom. The bracket may be permanently attached to a wall or other support or it may be hung in place so that it can be moved whenever desired 40 and thus used in traveling.

A device of substantially the proportions illustrated, will accommodate and successfully squeeze the contents from tubes of a range of sizes comprising the more 45 commonly used sizes; and for the very large sizes, a device of larger proportions may be provided.

But it may be desirable to use the squeezing key without the bracket and in Fig. 4 I have shown a squeezing key 22 comprising a head and a solid grooved shank adapted to receive the closed end 21 of the tube. By turning this key the tube can be wound up thereon in a manner substantially similar to 55 that before described.

The key may be stamped up from sheet metal and in Fig. 5 I have shown a blank 23 which may be stamped to form the key 24 of Fig. 6, this key being suitable for use 60 in place of the key 22 in Fig. 4.

My invention provides a simple and convenient means for squeezing a collapsible tube to discharge the contents thereof in such quantities as may be desired and with-

out loss of the contents and without breaking or cracking the tube. Furthermore, it provides a means for emptying the tube of its contents without leaving any appreciable amount remaining therein, at the same time protecting the surroundings, where the 70 bracket is employed.

I am aware that changes in the form, construction and proportion of parts of my invention may be made without sacrificing the advantages thereof, and I reserve the right 75 to make all such changes as fairly fall within the scope of the following claims.

I claim:

1. Means for squeezing a collapsible tube to discharge the contents thereof and comprising a back support plate, a top plate and side plates, said top plate having apertures to receive various sizes of collapsible tube caps and provided with a curved lip adapted to hold various articles used in connection with the contents of the tube, a winding key mounted in said side plates and having a shank located between the plates and provided with means to receive the closed end of a tube whereby the said tube 80 may be suspended from the shank of the key in front of the said back support plate and be wound upon the key.

2. Means for squeezing a collapsible tube to discharge the contents thereof and comprising a back plate provided at its lower end with a drip cup, a top plate and side plates, said top plate having apertures to receive various sizes of collapsible tube caps and provided with a slotted lip adapted to hold various articles used in connection with the contents of the tube, a winding key mounted in the said side plates and having a shank located between the side plates and provided with means to receive the closed 85 end of a tube whereby the said tube may be suspended from the shank of the key in front of the said back support plate and be wound upon the key.

3. Means for squeezing a collapsible tube 90 to discharge the contents thereof and comprising a back support plate having a portion thereof, pressed outwardly to give rigidity thereto and provided at its lower end with a drip cup, a top plate and side plates, said top plate having apertures to receive various sizes of collapsible tube caps and provided with a curved and slotted lip adapted to hold various articles used in connection 95 with the contents of the tube, a winding key mounted in the said side plates and having a shank located between the side plates and provided with means to receive the closed end of a tube whereby the said tube may be suspended from the shank of the key in front of the said back support plate and be wound upon the key.
